UNITED STATES PATENT OFFICE.

PAUL V. SMITH, OF LYONS, KANSAS.

TELEPHONE SYSTEM.

No. 902,388.

Specification of Letters Patent.

Patented Oct. 27, 1908.

Application filed December 22, 1906. Serial No. 349,134.

To all whom it may concern:

Be it known that I, PAUL V. SMITH, a citizen of the United States, residing at Lyons, in the county of Rice and State of Kansas, 5 have invented new and useful Improvements in Telephone Systems, of which the following is a specification.

The invention relates to an improvement in telephone systems designed primarily for 10 rural telephone service, comprehending specifically a means whereby the central operator may call one subscriber on a many party line without calling any other phone on the same line.

15 The main object of the present invention is the provision of a dial at each telephone subscriber's station, and controlling the movement of all of said dials from a fixed dial at the central station, each of the subscriber's 20 dials differing in arrangement of contacts from the others, whereby the energization of a call circuit at a particular point in the operation of the subscribers' dials, will energize only that call circuit in which the particular subscriber's dial is arranged to present a proper contact.

25 The invention will be described in the following specification, reference being had particularly to the accompanying drawings, in 30 which:—

Figure 1 is an elevation illustrating the arrangement of the controlling dial and one of the subscriber's dials, the contacts of the latter and the wiring therefor being illustrated. 35 Fig. 2 is an enlarged transverse section through a portion of the controlling dial, illustrating particularly the means for securing the respective contacts, Fig. 3 is a dia- 40 grammatic view showing a series of subscribers' dials.

Referring particularly to the drawings, wherein similar reference numerals indicate like parts throughout the several views, my improved automatic call system comprises a 45 controlling dial 1 and a series of subscribers' dials 2, one of each of the latter being arranged adjacent the telephone of each subscriber on a party line. The disk 1 is fixed, while each of the disks 2 is revolvably supported upon a 50 stud 3, and carry upon their rear faces toothed wheels 4 with which an escapement 5 is arranged to coöperate, the escapement lever 6 being projected below the pivotal point and shaped to provide an armature 7 for an 55 electro-magnet 8 fixed beyond the periphery of the disk.

The controlling dial 1 is formed adjacent its peripheral edge with a series of push buttons 9, one for each of the subscriber's dials. The push button 9 is mounted for movement 60 in a recess 10 formed in the controlling disk, said button carrying at its lower end a depending pin 11. The annular contact plate 12 is arranged in the peripheral edge of the disk 1, being so positioned that the recesses 65 10 are partly formed through said plate 12, so that the push button 9 at all times is in electrical contact with the plate 12. The bottom of the recess 10 is closed by a second contact plate 13, and between said plate and 70 the bottom of the push button 9 is arranged a coil spring 14 designed to normally support the button 9 to maintain the pin 11 out of contact with the plate 13. The escapement magnets 8 of each of the subscriber's 75 dials are connected in series through a conductor 15, terminally connected to the contact plate 12, the remaining conductor of a circuit 16 being connected to a pivot pin 17 secured centrally of the controlling dial on 80 the upper end of which is pivotally mounted a metallic handle 18 adapted for engagement with any one of the push buttons 9.

A catch magnet 19 is arranged adjacent each of the subscriber's dials, being provided 85 with a pivoted armature 20 which, when released from the influence of the magnet, is normally disposed in the path of a catch 21 secured upon the periphery of the subscriber's disk. The catch is pivotally supported on ears projecting from the disk and is provided with a laterally extending lip 22 so arranged relative to the plane of the catch proper as to prevent movement of the catch in one direction when the latter is in a particular position, so that the armature 20, when in normal position will engage the catches on the respective subscribers' dials and prevent movements of the dials. In this connection it is to be noted that the catch 90 21 proper when in engagement with the armature is inclined rearwardly from the vertical, so that upon depression of the armature through energization of its magnet the catch 95 21 gravitates to a vertical position and beyond influence of the armature, therefore, energization of the respective catch magnets 100 will free each of the subscriber's dials, without necessitating movement of said dials. 105

The catch magnets throughout the respective series of subscribers' dials are connected in series through a conductor 23, terminally 110

connected to the contact plate 13, the conductor 24 for completing the circuit being connected to the conductor 16 leading from the escaping magnets. So far described the 5 subscribers' dials are of identical construction and arrangement, but as it is desired that said dials perform an individual function, a variation in their connection to accomplish such function must be provided. 10 To this end each of the subscriber's dials is provided with a contact ring 25, preferably arranged adjacent the peripheral edge of the dial and adapted to be electrically engaged by a contact plate or brush 26 at all times. 15 The brushes for the series of subscribers' dials are connected in multiple through a conductor 27, terminally connected to the conductor 16 adjacent the controlling dial, the second conductor of this circuit, as 28, 20 being connected to the conductor 23 adjacent its connection with the contact plate 13. The conductor 28 connects in multiple a plurality of bell magnets 29, one for each subscriber's dial, said bell magnets forming the 25 energizing or bell sounding magnet for each telephone call bell. The remaining terminal of the winding of each magnet is projected beyond the same, as at 30, and terminates in a contact 31 disposed directly above or 30 spaced from the subscriber's dial. The contact ring 25 of each dial is formed with a projection 32 designed, when the particular dial is properly positioned to engage the contact 31 of the bell magnet winding and close the 35 circuit through said bell magnet.

Each of the push buttons 9 on the controlling dial corresponds to one of the subscribers' dials, and with all of said subscribers' dials arranged in the same relative 40 position, that with the catch 21 in engagement with the armature of the catch magnet the contact 32 of each dial will occupy a position corresponding exactly with the relative position of the push button of the particular subscriber's dial on the fixed controlling dial. That is to say the contacts 32 of the subscribers' dials will when said dials are 45 all in normal position be successively spaced a uniformly increased distance from the bell 50 magnet contact 31 and from each other, so that no two of the contacts 32 of any two subscribers' dials will occupy the same position relative to the contact 31.

With the parts constructed and arranged 55 as described and assuming the central operator desiring to call telephone number 4, he will initially depress any one of the push buttons 9 by engaging the handle 18 therewith and operating said handle, with the 60 effect to energize the catch magnets 19, and thereby release all of the subscribers' dials. The handle 18 is now moved from the operative or starting point into engagement with the push buttons up to and including that 65 button corresponding with dial 4. The con-

tact of the handle 18 with the successive buttons will operate the series of escapement magnets 8 and thereby move all of the subscribers' dials a distance corresponding to four teeth of the wheel 4. This movement 70 of the subscriber's dial will position the contact 32 of dial 4 to close the circuit through the contact 31 of the bell magnet of that dial. As the contact 32 of dial 4 is the only contact throughout the series of subscribers' dials, 75 which under the four step-by-step movements imparted by the dial will be positioned to engage the contact 31, it will be obvious that none of the other contacts 32 will be in engagement with the contact 31. Having 80 positioned the dials as described the operator depresses the handle 18 with the effect to force the particular push button 9 into engagement with the plate 13. This movement closes the circuit through the brush 26 85 and bell magnets 29, but as the circuit can only be closed through a particular bell magnet engaged by the contact 32 of the dial 4, this magnet alone is energized and hence the bell of telephone 4 alone is sounded. After 90 calling the particular telephone the operator returns the handle 18 to normal position, and then moves the latter a complete circle about the controlling disk, engaging each of the push buttons 9 and operating the escapement 95 magnets 8 of each of the subscribers' dials. This movement of the subscribers' dials, therefore, will be continued until each of the dials rides into engagement with the armature 20 of the catch magnet 19, when the 100 dials are precluded from further movement until the catch magnets are again energized. The resetting movement just described is essential in repositioning all of the subscribers' dials to an identical normal position 105 in order that the next calling operation of the central operator may simultaneously and similarly affect each of the subscribers' dials.

It will thus be seen that in the use of the construction described the central operator 110 is enabled to call any particular telephone on a multiparty line without sounding any of the other telephones on the line, thereby dispensing with the particular signal call for each telephone and avoiding the sounding of 115 telephones on the line for which the call is not intended.

Having thus described the invention what is claimed as new, is:—

1. The combination with a plurality of 120 telephones, of a series of dials arranged in respective coöperation with said telephones, means for locking all the respective dials in normal position, a contact carried by each dial and adapted to close the bell circuit of the particular telephone with which the dial coöperates, the contacts of each of the dials having relatively different positions on each dial when the dials are within the influence of 125 the locking means, a controlling dial carrying 130

a fixed contact corresponding to each dial and a movable contact corresponding to all the dials, the fixed contact and movable contact forming the terminals of a circuit for imparting a step-by-step movement through all the telephone dials, and an additional fixed contact carried by the controlling dial and forming together with the movable contact the terminals of a circuit including the locking means for all telephone dials.

2. The combination with a plurality of telephones, of a series of dials arranged in respective coöperation with said telephones, means for locking all the respective dials in normal positions, a telephone bell circuit closing contact carried by each dial, said contacts having different positions on the respective dials when said dials are within the influence of the locking means, a controlling dial carrying a fixed contact for each of the telephone dials, and a movable contact corresponding to all of the telephone dials, said contacts forming the terminals of the circuit adapted to impart a step-by-step movement to all of the dials, a second fixed contact adapted in connection with the movable contact to form the terminals of a circuit and serving when energized to release the locking means of all of the telephone dials, and a push button normally engaging each of the first mentioned fixed contacts and adapted to be operated by the movable contact to engage the second fixed contact.

3. The combination with a plurality of telephones, of a series of dials arranged in respective coöperation with said telephones, means for locking all of the respective dials in normal position and a contact carried by each dial and arranged to close the bell circuit of the particular telephone, the contacts of each of the respective dials having a different position on each dial when the dials are in normal position, and a controlling dial carrying a fixed contact for each of the dials, and a movable contact corresponding to all of the dials, said contacts forming the terminals of a circuit adapted to impart a step-by-step movement to all of the dials, said controlling dial carrying a second fixed contact adapted for electrical connection with the movable contact for releasing the locking means of all of the dials, said movable contact and second fixed contact forming also the terminals of the respective telephone bell circuits.

4. The combination with a plurality of normally open call circuits, of a series of dials

each carrying a contact adapted when in position to close one of the call circuits, means for normally holding all of said dials in position to maintain their contacts out of call circuit closing position, a controlling dial carrying a fixed contact forming one terminal of a circuit including the locking means of all the dials, a second fixed contact carried by the controlling dial and forming one terminal of a dial operating circuit, means arranged in said operating circuit adjacent each dial for imparting a step-by-step movement to the dial in the energization of the circuit, an arm mounted on the controlling dial and forming the remaining terminal of the locking circuit and of the controlling circuit, and a series of push buttons carried by the controlling dial and adapted to be engaged by the arm, each of said push buttons being normally in electrical engagement with the first mentioned fixed contact and being adapted for movement by the arm to electrically engage the second fixed contact.

5. The combination with a plurality of normally open call circuits, of a series of dials each carrying a contact adapted when in position to close one of the call circuits, means for normally holding all of said dials in position to maintain their contacts out of call circuit closing position, a controlling dial carrying a fixed contact forming one terminal of a circuit including the locking means of all the dials, a second fixed contact carried by the controlling dial and forming one terminal of a dial operating circuit, means arranged in said operating circuit adjacent each dial for imparting a step-by-step movement to the dial in the energization of the circuit, an arm mounted on the controlling dial and forming the remaining terminal of the locking circuit and of the controlling circuit, and a series of push buttons carried by the controlling dial and adapted to be engaged by the arm, each of said push buttons being normally in electrical engagement with the first mentioned fixed contact and being adapted for movement by the arm to electrically engage the second fixed contact, the terminals of the respective call circuits including the movable arm and the second fixed contact.

In testimony whereof, I affix my signature in presence of two witnesses.
